United States Patent

Des. 235,234
Patented June 3, 1975

235,234

OTTOMAN

Jerry Johnson, Rancho Cuello, Box 50,
Portrero, Calif. 92063

Original design application May 10, 1973, Ser. No.
359,007. Divided and this application July 17, 1974,
Ser. No. 489,079

Term of patent 14 years

Int. Cl. D6—01

U.S. Cl. D6—36

FIG. 1

FIG. 2

FIG. 3

FIG. 4

FIG. 1 is a perspective view of a ottoman showing my new design;

FIG. 2 is a side elevational view showing the side not visible in FIG. 1 thereof;

FIG. 3 is a top plan view thereof; and,

FIG. 4 is a bottom plan view thereof.

This application is a division of my earlier filed case Ser. No. 359,007, filed May 10, 1973.

I claim:

The ornamental design for an ottoman, substantially as shown.
